UNITED STATES PATENT OFFICE.

FRANK E. KEYES, OF NEW YORK, N. Y.

STRAINER.

1,007,449.

Specification of Letters Patent. Patented Oct. 31, 1911.

Application filed November 5, 1910. Serial No. 590,922.

To all whom it may concern:

Be it known that I, FRANK E. KEYES, of New York, in the county of New York and State of New York, have invented certain new and useful Improvements in Strainers; and I do hereby declare the following to be a full, clear, and exact description of the invention, such as will enable others skilled in the art to which it appertains to make 10 and use the same.

This invention relates to improvements in strainers,—the object of the invention being to provide a strainer which can be readily applied to a water fountain of any 15 construction; which will effectually separate flocculent matter from the water and permit it to be deposited out of the path of incoming water; and which can be easily and quickly taken apart and effectually cleaned.

20 With this object in view the invention consists in certain novel features of construction and combinations of parts as hereinafter set forth and pointed out in the claim.

25 In the accompanying drawings, Figure 1 is a longitudinal sectional view of my improved strainer, and Fig. 2 is an end view.

1 represents a cylinder which may conveniently be made of bronze and provided 30 at one end with a threaded opening 2 for the passage of an outlet nipple 3,—an inlet opening 4 being provided near the other end of said cylinder. The end of the cylinder near the inlet opening 4 is made with 35 a large opening having threaded walls for the accommodation of a head 5. The head 5 is made cup-shaped to form a sediment chamber 6 and the exterior of said head is adapted for the reception of a suitable 40 wrench. An annular flange 7 projects from the head 5 and forms a portion of the sediment chamber 6. The lower end of a perforated tube 8 encircles the flange 7 and is secured thereto,—said perforated tube being 45 of sufficient length to extend approximately to the opposite end of the cylinder and having a diameter appreciably less than that of the cylinder. The upper end of the tube 8 is closed by a head 9 and through this head 50 the outlet nipple 3 projects. A covering 10

of wire gauze (preferably of about 200 mesh) surrounds the perforated tube and closely embraces the same. Water entering at 4 will flow into the chamber 11 formed between the cylinder and the straining tube 55 and pass from said chamber through the wire gauze covering 10 and through the perforations of the tube 8 and find an exit through the outlet nipple 3. Any flocculent matter which may be contained in the water 60 will be caught by the gauze covering 10 and fine impurities which might remain in suspension in the water after the latter reaches the interior of the tube 8 will become deposited in the sediment chamber 6. 65

By removing the head 5, the tube 8 and its gauze covering 10 will also be removed from the cylinder and can be readily cleaned by running water through the perforated tube and the gauze from a suitable faucet, when 70 the sediment will be effectually removed from the meshes of the gauze and from the sediment chamber.

Having fully described my invention what I claim as new and desire to secure by 75 Letters-Patent, is,—

A water strainer comprising a cylinder provided near its lower end with a water inlet, a head passing through the bottom of the cylinder and removably supported 80 thereby, said head having a cup-shaped portion constituting a sediment chamber, a perforated tube secured to said head and having a diameter appreciably less than the internal diameter of the cylinder, said tube 85 extending approximately to the upper end of the cylinder and having a closed head at its upper end, an outlet nipple projecting through the upper end of the cylinder and through the head at the upper end of the 90 perforated tube and removable therefrom, and a gauze covering inclosing said perforated tube.

In testimony whereof, I have signed this specification in the presence of two subscribing witnesses. 95

FRANK E. KEYES.
